PROCESS FOR THE TREATMENT OF
HYDROCARBON OIL

Frederick W. Sullivan, Jr., and Robert F. Ruthruff, Hammond, Ind., assignors to Standard Oil Company, Chicago, Ill., a corporation of Indiana

Application December 1, 1934, Serial No. 755,538

11 Claims. (Cl. 196—49)

This invention relates to processes for the treatment of hydrocarbon oil and pertains more particularly to the production of lower boiling point oil from higher boiling point oil.

5 It is an object of our invention to provide an improved process for the formation of gasoline or other relatively light distillate from crude oil, or the like, according to which the entire amount of cracking is carried out substantially on a once-through basis with only a small amount of recycling, whereby the amount of oil pumped through the cracking zones is not greatly in excess of the amount of charging stock subjected to the process.

15 Processes are now known wherein crude charging oil or the like is subjected to distillation with the resulting formation of an intermediate condensate in the nature of gas oil suitable for use as clean cracking stock, and reduced crude, as well as a quantity of final desired light distillate, if the charging stock contains constituents light enough to form such final desired distillate. The intermediate condensate is then subjected to cracking to form additional quantities of final 25 desired light products and intermediate condensate which is recycled to the cracking zone for further conversion. At the same time the reduced crude or other residual liquid is subjected to a cracking operation, such as to cause the 30 formation of additional quantities of intermediate condensate stock suitable for mixture with the gas oil condensate derived from the initial charging stock, and this additional condensate is subjected to conversion in the cracking operation first-mentioned with the intermediate gas 35 oil condensate from the initial charge. These processes are open to the objection that the cracking conditions in the zone in which the intermediate condensate is cracked, must be selected with a proper regard for the presence in the oil undergoing cracking of constituents recycled from the cracking operation, which have a greater coke-forming tendency than the initial condensate derived from the crude charging 40 stock. It has been supposed heretofore that a cycle stock derived from a cracking operation always has greater coke-forming tendencies than the initial cracking stock from which it was formed, and cracking conditions have been adjusted accordingly.

We have now found that the cycle stock derived from the initial cracking of the intermediate distillate removed from crude oil charging stock, or the like, does not have such deleterious 55 coke-forming tendencies as are associated with

cycle stock from known cracking processes, but that, on the other hand, if the conditions under which the initial cracking step is carried out are properly selected, cycle stock so obtained has substantially the same cracking characteristics 5 as the initial intermediate distillate charging stock and may be converted at relatively high percentages of cracking per pass, under substantially the same conditions as the initial intermediate distillate charging stock. We have found 10 cycle stock derived by the cracking of cycle stock from the initial cracking operation conducted on said intermediate distillate stock is, on the other hand, of decidedly different character from the fresh distillate charging stock and has rather 15 marked coke-forming tendencies such as prevent it from being cracked successfully under substantially the same conditions of temperature and pressure and conversion per pass as used in connection with the fresh distillate charging stock. 20

In accordance with our invention fresh relatively heavy charging stock such as crude oil, partially topped crude, or the like, is subjected to distillation after having been preheated in a suitable fashion, as for example by indirect heat 25 exchange with hot products from the following cracking steps or by passage through a directly fired coil in a heating zone, to form an intermediate condensate of a gas oil nature suitable for use as clean cracking stock, a reduced crude, 30 and also a quantity of final desired light distillate, if the fresh charging stock contains constituents light enough to go into this distillate. There may likewise be formed an intermediate cut such as kerosene, distillate fuel oil, or the 35 like, which may be withdrawn as a final desired product, as well as a heavy naphtha cut which it is desired to reform in order to produce relatively high anti-knock gasoline constituents.

The intermediate gas oil condensate is then 40 passed once through a first cracking zone wherein it is raised to a relatively high cracking temperature under relatively high super-atmospheric pressure, without recycling, and is subjected to conversion such as will result in the formation of 45 relatively large quantities of products in the gasoline boiling range. The resulting cracked products are separated into vapors and liquid residue, the latter being withdrawn from the process, while the former are subjected to fractionation 50 to form a final desired light distillate, e. g., gasoline, and a reflux condensate of a gas oil nature. This reflux condensate is then passed once through a second cracking zone wherein it is subjected to conversion under substantially the 55

same conditions of temperature, pressure and conversion per pass as are used in the cracking zone first-mentioned, without recycling, the resulting cracked products are separated into vapors and liquid residue, and the residue is withdrawn from the process while the vapors are subjected to fractional condensation to form additional quantities of the desired light distillate, e. g. gasoline, and reflux condensate. The latter being of a refractory nature, is preferably diverted from the process as a distillate fuel oil, but may, if desired, be passed to a third cracking zone wherein it is cyclically cracked to completion in the vapor phase or otherwise, in accordance with known practices, to form additional quantities of final desired light distillate and residue.

Simultaneously the reduced crude or residual portion of the fresh charging stock is passed through a viscosity breaking cracking zone and is therein raised to a cracking temperature and subjected to conversion under relatively mild conditions, such as will result in the formation of only relatively small percentages of the final desired distillate such as gasoline, but will produce considerable quantities of intermediate fractions suitable for use as a cracking stock for the first-mentioned cracking step. The resulting mildly cracked products are separated into vapors and liquid residue and the latter is withdrawn from the process while the former are subjected to fractional condensation to form more of the final desired light distillate such as gasoline, and quantities of intermediate condensate stock of a gas oil nature, and this latter condensate is combined with the intermediate condensate from the initial distillation stage for passage through the cracking zone first-mentioned. A heavier condensate than said intermediate condensate may likewise be formed and be returned to the said viscosity breaking cracking zone, if desired.

In conducting the operation as outlined hereinbefore the cracking temperature in the first and second-mentioned cracking zones is preferably in the range of 970° to 1100° F., while the pressure in each of these zones preferably falls in the range of 700 pounds to 1200 pounds per square inch, the time of contact being such that a conversion to products in the gasoline boiling range per pass of at least 40% or more will result. The viscosity breaking cracking operation carried out on the reduced crude is much less drastic, being such as to produce not more than about 15% conversion per pass of products in the gasoline boiling range being, for example, such as to cause a conversion per pass of about 8%-10%, a suitable temperature range being from 840° to 900° F., more or less, and a suitable pressure range being from a few pounds to several hundred pounds per square inch, for example, from 150 pounds to 300 pounds per square inch. In case a cut of heavy naphtha is removed from the crude distilling zone, which it is desired to reform in order to raise the anti-knock value of the final desired distillate, this heavy naphtha is passed through a separate reforming zone wherein it is raised to a relatively high cracking temperature suitable to cause the conversion of the heavy naphtha into higher anti-knock gasoline constituents, and the resulting highly heated reformed products are preferably introduced into the zone into which the cracked intermediate condensate or gas oil from the first-mentioned cracking zone is passed for separation into vapors and liquids. The temperature under which reforming may be carried out is preferably

in the range of 950° to 1150° F. more or less, while the pressure may vary considerably, being from a few pounds to several hundred pounds per square inch, for example about 700 pounds per square inch.

Instead of separately cracking gas oil and reforming heavy naphtha to give the desired high anti-knock characteristics to the final light distillate, the heavy naphtha and gas oil may be passed together in a mixture through the initial once-through cracking zone and therein be subjected to conversion at the same time, the gas oil undergoing cracking and the heavy naphtha at the same time being subjected to reformation. Where the mixture is treated in a common cracking zone in this way the temperature to which the stock is elevated may be higher than where the gas oil alone is subjected to cracking. This same method of operation may be utilized in connection with the cracking of the cycle stock from the first stage cracking operation; the cycle stock or reflux condensate resulting from the fractionation of the cracked vapors then comprising not only gas oil constituents but also heavy naphtha constituents, in which event additional reformation of the cracked heavy naphtha or heavy ends of gasoline would take place with an attendant increase in the anti-knock value of the desired light distillate.

In this case the fractionated vapors from the first cracking stage would consist essentially of light naphtha, while the end point gasoline distillate would be removed from the fractionator of the second cracking stage and the final desired distillate could be formed by blending these two distillates in desired proportions, while adding, if desired, light naphtha or virgin gasoline from the crude distilling zone.

The above-mentioned and further objects and advantages of our invention and the manner of attaining them will be more fully explained in the following description taken in conjunction with the accompanying drawing.

The single figure of the drawing represents diagrammatically an oil cracking system embodying our invention.

Referring more particularly to the drawing, reference numeral 1 indicates a crude flash tower or stripping tower, into which crude oil or the like is introduced through charging line 2, by aid of pump 3, after having been preheated in any desired manner, as by passage through indirect heat exchange coils in contact with highly heated products resulting from subsequent cracking steps, or by passage through a directly fired heating coil, or both.

In the tower 1 the introduced crude charging oil separates into vapors and liquids, the former passing upwardly through the tower past bubble trays, baffle plates or other similar well known contacting means, while the liquid gravitates downwardly through the tower, over similar trays if desired, the vaporizing action being aided by the application of heat to the base of the tower through the agency of reboiler coil 4, or by the introduction of hot gases or steam in accordance with the known practice. In their passage upwardly through the tower the generated vapors undergo fractionation, the fractionated vapors passing from the top of the tower through vapor line 5 and condenser 6, resulting condensate being collected in receiver 7. This condensate may be light naphtha, gasoline, or other desired light distillate. At an intermediate point in the tower 1 a trap-out tray 8 is located, which serves to col-

lect an intermediate condensate of a gas oil nature suitable for use as clean cracking stock, this gas oil being removed through line 9 having pump 10, and forced through the heating coils of cracking heater 11, wherein the oil is raised to a relatively high cracking temperature, falling, for example, in the range of 970° to 1100° F. under an outlet pressure of a relatively high value, falling most desirably in the range of 700 pounds to 1200 pounds per square inch, and being preferably about 1000 pounds per square inch, the time of contact being such that a conversion to products in the gasoline boiling range per pass, of at least 40%, is obtained although the value may exceed 40% being 45% or even more.

The resulting cracked products pass through the transfer line 12, having pressure control valve 13, into separating chamber or evaporator 14, wherein vapors separate from liquid residue. The vapors pass upwardly through the tower, undergoing partial fractionation if desired by passage through bubble trays or other suitable contacting elements 15, any necessary cooling being provided by indirect heat exchange coil 16, or by the introduction of a cooling oil in accordance with well known practices. The vapors travel through vapor line 17 into the fractionator 18 wherein fractionation thereof takes place in the usual way forming vapors of desired boiling characteristics and a reflux condensate. The fractionated vapors are conducted through pipe 19 into condenser 20, from which condensate flows into the receiver 21, this condensate constituting a desired light distillate, e. g. gasoline.

While the preceding cracking operation is taking place the liquid reduced crude is withdrawn from the base of the crude flash tower 1 and forced by pump 22 through conduit 23 and the heating coils or furnace 24, wherein the oil is raised to a cracking temperature and subjected to only a moderate amount of conversion into products in the gasoline boiling range, with the attendant formation of additional quantities of gas oil constituents suitable for cracking in the heater 11 with the virgin stock withdrawn from trap-out tray 8. The oil during its passage through the heater 24 may be, for example, raised to a cracking temperature falling in the range of 840° to 900° F., the outlet pressure being, for example, from a few pounds to several hundred pounds per square inch, preferably falling in the range of from 150 pounds to 300 pounds per square inch, while the time of contact is such that the amount of conversion to products in the gasoline boiling range per pass is relatively low, being most desirably not over 15% per pass, preferably being about 8% to 10% per pass.

The cracked oil so produced is conducted through transfer line 25, having pressure control valve 26, into the separating chamber or evaporator 27, in which the separation of vaporous products from liquids is effected. The vapors pass upwardly through the tower and are subjected to partial fractionation by the agency of baffle plates, bubble trays, or other contacting means, the fractionation being aided by cooling supplied to the top of the tower, for example by means of indirect heat exchange coil 28. In place of this indirect heat exchange coil a cooling fluid might be introduced directly into the top of the tower. Additional cooling may be supplied below the trap-out tray 29 if desired. This trap-out tray serves to collect a relatively heavy condensate of a heavy gas oil nature which is not suitable for passage through a cracking zone wherein

relatively drastic cracking conditions are maintained, but may be subjected to additional conversion in the viscosity breaking heater 24. This stock is therefore returned to the heating zone through conduit 30 having pump 31, and is additionally cracked in the heater mentioned.

The partially fractionated vapors are conducted through the connecting pipe 32 into the fractionating column 34, which is equipped with the usual bubble trays or similar contacting means, and serves to fractionate the vapors in the well known manner, to separate undesirably heavy constituents, as reflux condensate, which collects in the base of the tower, from desirably light constituents, which pass from the top of the tower in vapor form. These light constituents travel through vapor line 35 into condenser 36, resulting condensate being collected in receiver 37, as a desired light distillate, e. g. gasoline.

The reflux condensate from the bubble tower 34 is passed through conduit 38 into line 9 in which it mixes with virgin stock from the tower 1, for passage through the heating coils of cracking furnace 11, wherein it is subjected to the cracking treatment as described already in connection with the intermediate gas oil condensate from the tower 1. Or part or all of the reflux from bubble tower 34 may be commingled with the reflux from tower 18, in conduit 41, for cracking therewith in heater 39, valved cross-over line 39' being provided for this purpose.

Reflux condensate from the base of fractionator 18 is withdrawn through pipe 41 and forced by pump 40 through the coils of cracking heater 39. In passage through the heater 39 the oil is subjected to substantially the same cracking conditions of temperature, pressure, and time, as already described in connection with the cracking operation taking place in the heater 11, the resulting cracked products passing through transfer line 44 having control valve 45, into the evaporator 46, wherein an action similar to that taking place in the tower 14 occurs. This tower may have baffle plates, bubble trays, or other contacting elements and an indirect cooling coil 45 or other cooling means, as already described in connection with evaporator 14. In this tower partial fractionation occurs, the resulting fractionated vapors traveling through the connecting pipe 47 into the fractionator 48 wherein fractionation thereof takes place in the usual well known manner by aid of bubble plates or other contacting elements contained in the tower and an indirect cooling coil or other suitable cooling arrangement at the top of the tower. The fractionated vapors are removed from the tower and pass through the conduit 49 into condenser 50, from which the condensate emerges and is collected in receiver 51 as a desired light distillate, e. g. gasoline. Portions of the condensate formed in the tower 34 may be withdrawn from the process through pipe 42 and similarly portions of the condensate formed in the tower 18 may be withdrawn from the process through pipe 43, to establish balanced operating conditions, or if desired, additional quantities of similar oil may be supplied to the process through these same connections for a like purpose.

The distillates collected in receivers 1, 21, 37 and 51, or any combination of them, may be blended to produce a final desired light distillate, the blending being accomplished by way of lines 52 and 53. Alternatively all or part of the distillate may be drawn off from the receivers mentioned by way of draw-off lines 54, 55, 56 and 57, 75

respectively. Reference numerals 58, 59 and 60 indicate draw-off lines by means of which liquid residue or tar may be withdrawn from the evaporators 21, 14 and 46, respectively, while reference numeral 61 indicates a draw-off line by means of which reflux condensate formed in the fractionator 48 may be diverted from the process as a distillate fuel oil or for any other use. If desired, this condensate from line 61 may be passed to a separate cracking unit (not shown) wherein it is cracked to completion in any well known manner, preferably in a vapor phase low crack per pass recycling operation.

Simultaneous with the carrying out of the preceding cracking steps, where it is desired to raise the anti-knock value of the final distillate to a high value, a cut of heavy naphtha may be collected on trap-out tray 62 of the crude flash tower 1, be withdrawn through pipe 62 and passed through the coils of reforming heater 63, by action of pump 64. In its passage through this heater the heavy naphtha is raised to a relatively high cracking temperature sufficient to cause the reformation of the naphtha and the conversion thereof into relatively high anti-knock gasoline constituents. The resulting reformed products pass through transfer line 65, having pressure control valve 66, preferably into the evaporator 14 with the cracked products from the cracking heater 11, and therein undergo separation into vapors and liquids, as already described in connection with the cracked products from the heater 11. But if desired the hot reformed products may instead be introduced directly into evaporator 46. Or the heavy naphtha may be introduced directly into the coils of heater 39 for cracking in mixture with the gas oil.

As an alternative to carrying out a reforming action in the heater 63, the fractionation of the vapors in the crude flash tower 1 may be so regulated that a mixture of heavy naphtha and gas oil is collected on the trap-out tray 8 for passage through the cracking heater 11. In this event the reformation of the heavy naphtha would be carried out in the heater mentioned, and to insure this the outlet temperature of the heater may be raised somewhat above the value used in connection with the cracking of gas oil alone.

Similarly the fractionation in the towers 34 and 18, or either of them, may be so controlled that the reflux condensate collected in the base thereof is a mixture of heavy naphtha and gas oil, the gas oil constituents being subjected to cracking and the heavy naphtha constituents being subjected to reforming in the following heaters. In this case the outlet temperature of the heater 39 may likewise be elevated somewhat in order to increase the reformation taking place therein.

Alternatively the gas oil and heavy naphtha constituents formed in the fractionators 34 and 18 might be separately collected in those towers and be passed through separate heating coils corresponding to heaters 11 and 39 respectively, so that the cracking of the gas oil and the reforming of the heavy naphtha would be carried out separately under the most advantageous conditions, the evaporators 14 and 46 being used to receive both the cracked and reformed products, or separate evaporators being used in cases where separate withdrawal of different cracked products is desired.

According to an alternative arrangement the method of operation would be to divide the charg-

ing stock introduced into the tower 1 into only an overhead fraction, including the desired light distillate and a liquid fraction collected in the base of the tower, this latter including constituents as light as gas oil or even heavy naphtha. This entire cut would then be subjected to a viscosity breaking cracking action in the heater 24, under preferably slightly more drastic conditions than used in carrying out the viscosity breaking action on the reduced crude alone as described hereinbefore. The cracked products obtained would then be treated just as described in connection with the preferred embodiment already hereinabove illustrated, except that the virgin gas oil and heavy naphtha would be absent.

A still further modification would be to carry out the cracking in the viscosity breaking heater 24, of the mixture of heavy constituents and lighter ones of a gas oil and even heavy naphtha nature, as already mentioned, and then to form from the resulting cracked products two different reflux condensate stocks, one being a clean intermediate condensate of a relatively light gas oil nature, including even some heavy naphtha constituents, while the other would be a heavier gas oil condensate of less clean characteristics. These two stocks would then be subjected to cracking in separate furnaces and be introduced into a common evaporator corresponding to 14, or separate evaporators if desired, the resulting vapors being subjected to fractionation in a fractionator corresponding to 18, or in separate fractionators, and the reflux condensate obtained might either be passed in its entirety to the cracking heater 39 and evaporator 46, as mentioned in the already described process, or the reflux condensate might be divided into a light and a heavy cut and these be passed through separate cracking furnaces and combined in the evaporator 46, or in separate evaporators if desired, to effect separate tar withdrawal.

In carrying out the modified form of operation wherein the reflux condensates from the several cracking steps are divided into two cuts, one an intermediate condensate and the other a somewhat heavier condensate; the cracking conditions used would be slightly less drastic for the heavy stock than for the lighter stock, on account of the greater coke-forming tendency of the heavier stock. The conditions under which the lighter of the constituents is cracked may be somewhat more drastic than those mentioned in connection with the cracking of the intermediate condensate in the preferred embodiment first described, in case the lighter of the two condensates of this modification is somewhat lighter than the intermediate condensate of the preferred embodiment.

Our invention as described hereinbefore permits the production from relatively heavy initial charging stock, which is itself not suitable for very drastic cracking, of relatively large quantities of high anti-knock gasoline, the preliminary viscosity breaking stage serving to produce a very clean cracking stock suitable for very high cracking per pass in the subsequent high-pressure cracking operation. Since this subsequent cracking operation is carried out under high pressure and high temperature conditions, gas production is minimized, while the production of tar is somewhat encouraged, both of these actions having a tendency to keep the hydrogen content in the cycle stock up to a satisfactory value, whereby this first cycle stock is suitable for subsequent cracking under substantially the same conditions

as maintained in the cracking of the initial distillate stock.

In the drawing various valves and other apparatus not specifically identified are for obvious control purposes.

The cooling coils not supplied directly with reference numerals perform their usual function. The fresh charging stock may be preheated prior to its introduction into the crude flashing tower 10 by passage through some or all of the cooling coils shown on the drawing.

The heating coils for carrying out the several cracking operations may be located in separate furnaces as shown, or all of them may be placed in one furnace, or some may be placed in one furnace and the others in one or more separate furnaces. If desired, enlarged reaction chambers may be placed in the path of the oil from the cracking coils to the evaporators, in which 20 case part of the cracking might be carried out in the coils and the remainder in the reaction chambers, but ordinarily it is preferable to effect all of the cracking in the coils.

The pressures maintained in the several evaporators may vary considerably, but preferably fall in the range of 150 pounds to 300 pounds per square inch, more or less. Undesirable coking in these evaporators may be inhibited by supplying cooling to the bases thereof in any well known 30 manner.

In carrying out our invention on a charging stock such as 36° A. P. I. gravity Mid-Continent crude oil, the constituents removed from the crude flashing zone may be 10% to 30% light naphtha, 35% to 45% gas oil, and 35% to 45% reduced crude, the exact percentages varying considerably in accordance with the specific operating conditions and the specific character of the final products desired. Obviously, if virgin heavy naphtha is to be included in the gas oil charging stock for passage through the initial cracking zone so as to be reformed therein, the percentage of naphtha removed from the top of the crude flashing zone would be comparable with the lower percentage mentioned, while if substantially all of the virgin gasoline is taken off overhead, the higher percentage of the naphtha would prevail.

While we have described a particular embodiment of our invention for the purposes of illustration, it should be understood that various modifications and adaptations thereof occurring to one skilled in the art, may be made within the spirit of our invention as set forth in the appended claims.

We claim:

1. The process of treating hydrocarbon oil which comprises subjecting fresh relatively heavy uncracked charging stock to non-cracking distillation to form an intermediate gas oil condensate and an unvaporized fraction, passing said unvaporized fraction through a first cracking zone wherein it is raised to a cracking temperature and subjected to conversion into products in the gasoline boiling range of not more than about 15% per pass, separating the resulting cracked products into vapors and a liquid residue, fractionating said vapors to form a final desired light distillate and a clean intermediate condensate of a gas oil nature, combining said condensate last-mentioned with said intermediate condensate first-mentioned and passing the mixture once through a second cracking zone wherein the oil is raised to a cracking temperature of at least 970° F. under a superatmospheric pressure of at

least 700 pounds per square inch and is subjected to conversion such as to form the production of at least 40% of constituents in the gasoline boiling range, without recycling, introducing cracked products so obtained into a second separating zone wherein separation of vapors from liquid residue takes place, fractionating vapors so obtained to form a final desired light distillate and an intermediate condensate of a gas oil nature, passing gas oil condensate so obtained once through a third cracking zone wherein it is raised to a cracking temperature of at least 970° F., under a superatmospheric pressure of at least 700 pounds per square inch, and is subjected to conversion into products of the gasoline boiling range of at least 40% per pass, without recycling, introducing cracked products so obtained into a third separating zone wherein vapors separate from liquid residue, fractionating said vapors to form a final desired distillate and a reflux condensate and diverting said reflux condensate from the process.

2. A process in accordance with claim 1 wherein in the vapors from the cracked products first-mentioned are fractionally condensed to form a final desired light distillate, a clean intermediate condensate of a gas oil nature, and a heavier condensate; and said heavier condensate is returned to the first-mentioned cracking zone for additional conversion.

3. A process in accordance with claim 1 wherein in a heavy naphtha distillate is segregated from the vapors liberated in the first-mentioned distilling zone and passed through a reforming zone wherein it is raised to a cracking temperature and subjected to reformation, and resulting reformed products are introduced into said separating zone second-mentioned.

4. The process of treating hydrocarbon oil which comprises passing relatively heavy fresh uncracked charging stock of a residual nature through a cracking zone wherein it is raised to a cracking temperature and subjected to a moderate amount of conversion into lighter products in the gasoline boiling range, said conversion not exceeding 15% per pass, introducing the resulting cracked products into a first separating zone wherein vapors separate from liquid residue, passing said vapors to a fractionating zone and therein fractionally condensing them to form a final desired light distillate and a clean reflux condensate, passing said condensate once through a second cracking zone, without recycling, wherein it is raised to a cracking temperature of at least 970° F., under a superatmospheric pressure of at least 700 pounds per square inch, and is subjected to at least 40% conversion into products in the gasoline boiling range per pass, introducing cracked products so obtained into a second separating zone wherein vapors separate from liquid residue, passing liberated vapors into a second fractionating zone and therein fractionally condensing them to form additional quantities of the final desired light distillate and a clean reflux condensate, passing said clean reflux condensate once through a third cracking zone, without recycling, wherein it is raised to a cracking temperature of at least 970° F. under a high superatmospheric pressure, and is subjected to conversion into products in the gasoline boiling range of at least 40% per pass, introducing resulting cracked products into a third separating zone wherein vapors separate from liquid residue, fractionating resulting vapors to form additional quantities of final desired light distillate and a

reflux condensate, and diverting said reflux condensate from the process.

5. A process in accordance with claim 4 wherein there is mixed with said condensate derived from 5 said first-mentioned fractionating zone a quantity of virgin distillate stock of a boiling range similar to that of said condensate.

6. A process in accordance with claim 4 wherein said condensate derived from said first-mentioned 10 fractionating zone includes heavy naphtha components which it is desired to reform.

7. The process of treating hydrocarbon oil which comprises fractionally distilling crude oil charging stock, without cracking the same, to 15 form a clean intermediate condensate cracking stock including heavy naphtha constituents, and reduced crude, passing said reduced crude through a first cracking zone wherein it is raised to a moderate cracking temperature and subjected to 20 only mild cracking such as to form not over 15% of products in the gasoline boiling range per pass, introducing resulting cracked products into a first separating zone wherein vapors separate from liquid residue, passing said vapors to a first fractionating zone and therein fractionally condensing them to form a quantity of final desired light 25 distillate and a clean intermediate condensate, combining clean intermediate condensate so obtained with said intermediate condensate derived 30 from said crude oil charging stock and passing the resulting mixture once through a second cracking zone wherein it is raised to a cracking temperature of at least 970° F. under a superatmospheric pressure of at least 700 pounds per square 35 inch, and is subjected to conversion into products in the gasoline boiling range of at least 40% per pass, without recycling, introducing resulting cracked products into a second separating zone wherein vapors separate from liquid 40 residue, passing said vapors to a second fractionating zone and therein fractionally condensing them to form additional quantities of final desired light distillate and a clean intermediate condensate, passing intermediate condensate so obtained 45 once through a third cracking zone, without recycling, wherein it is raised to a cracking temperature of at least 970° F. under a high superatmospheric pressure and is subjected to conversion into products in the gasoline boiling range 50 of at least 40% per pass, introducing resulting cracked products into a third separating zone wherein vapors separate from liquid residue, passing said vapors to a third fractionating zone and therein fractionally condensing them to form 55 additional quantities of final desired light distillate and intermediate condensate.

8. A process in accordance with claim 7 wherein reflux condensate derived from said third-mentioned fractionating zone is withdrawn and cycli-

cally cracked to completion in a separate recycling-cracking unit at only moderate rates of conversion per pass.

9. A process in accordance with claim 7 wherein light naphtha is separated from said crude oil 5 charging stock and the final desired distillate is formed by blending said light naphtha with quantities of final desired light distillate obtained from said fractionating zones.

10. The process of treating hydrocarbon oil 10 which comprises subjecting fresh relatively heavy uncracked charging stock to non-cracking distillation to form an intermediate gas oil condensate and an unvaporized fraction, passing said unvaporized fraction through a first 15 cracking zone wherein it is raised to a cracking temperature and subjected to not more than 15% of conversion into products in the gasoline boiling range, separating the resulting cracked products into vapors and a liquid residue, fractionating said vapors to form a final desired light distillate and a clean intermediate condensate of a gas oil nature, passing said condensate first mentioned once through a second cracking zone wherein the oil is raised to a cracking temperature of at least 970° F. under a superatmospheric pressure of at least 700 pounds per square inch and is subjected to conversion such as to form the production of at least 40% of constituents in the gasoline boiling range, without recycling, introducing cracked products so obtained into a second separating zone wherein separation of vapors from liquid residue takes place, fractionating vapors so obtained to form a final desired light distillate and an intermediate condensate of a 20 gas oil nature, passing gas oil condensate so obtained once through a third cracking zone wherein it is raised to a cracking temperature of at least 970° F., under a superatmospheric pressure of at least 700 pounds per square inch, and is 25 subjected to conversion into products of the gasoline boiling range of at least 40% per pass, without recycling, introducing cracked products so obtained into a third separating zone wherein vapors separate from liquid residue, fractionating 30 said vapors to form a final desired distillate and a reflux condensate, diverting said reflux condensate from the process, and combining said intermediate condensate second-mentioned with one of said intermediate condensates first and 35 third-mentioned, for cracking therewith.

11. A process in accordance with claim 10 wherein said intermediate condensate second-mentioned is combined with said intermediate condensate third-mentioned, for cracking there- 45 with.
